UNITED STATES PATENT OFFICE

OSCAR ADOLF KRISTIAN PRINTZ, OF OVERUM, SWEDEN

RELEASEABLE PLOW

Application filed September 11, 1930, Serial No. 481,296, and in Sweden April 22, 1930.

This invention relates to releasable plows and more particularly to an improvement in the releasable plow which is set forth in my copending application Serial No. 342,830, filed February 2, 1929. In the specification of said application a spring controlled device is described and claimed which has for its object to allow the plow base to swing back when encountering an obstacle in the ground which overcomes the action of the spring in order thereby to avoid damage of the plow. According to said application the plow base which is pivotally connected to the plow frame, is held in working position by a spring controlled two-armed pivoted lever which is mounted freely both with respect to the spring and to the plow base or body, so that it has only frictional engagement therewith, the lever arm cooperating with the spring being so shaped as to relieve the plow base from the action of the spring already after a very slight compression of the spring due to a correspondingly slight turning of said lever out of its normal or locking position so that the spring will allow the necessary continued turning of the lever to effect the release of the plow beam without affording any increased resistance thereto. This will permit the use of a very powerful spring capable of securing a steady motion of the plow base irrespective of varying resistance in the ground.

In the device above referred to that arm of the two-armed lever which cooperates with the spring is formed with a cam surface having a portion which is concentric or substantially concentric with the centre of movement of the lever. After the lever has been turned slightly from its normal position to compress the spring, as above stated, the spring will come to act upon the said concentric portion. The spring action is transmitted to said cam surface by a roller which is carried by a sliding member directly acted on by the spring and sliding in a suitable bearing. In the released position of the lever, that is to say, with the spring compressed and the plow base swung back out of engagement with the lever, a serious wedge-action will be produced between said cam surface and said roller and the upper portion of said bearing as result of the relative position of said parts. The stress on said parts as well as the friction therebetween will be very large due to the powerful spring used, and may result in breakage of said parts or in such a wear or deformation of the cam surface that the device cannot act in the manner desired, especially, that the plow base cannot be brought back to working position against the action of the spring by a backward drive of the plow. The object of this invention is to overcome said drawbacks. The invention is characterized, chiefly, by the provision of a movable stop member controlled by said two-armed lever and adapted to be held out of engagement with the spring, as long as the lever holds the plow base in working position, but will be brought to a position in which it will take up the spring pressure and prevent the same from acting on the lever, as soon as the lever is moved to release the plow base.

In the accompanying drawings one embodiment of the invention is shown. Fig. 1 is a side elevation of the plow base in working position, and Fig. 2 is a side elevation of the plow base, after it has been released and swung back.

The plow beam 2 with the plow base 3 is mounted in the plow frame 1 by a pivot 4 which connects the bearing member 5 attached to the plow beam 2 with the bracket 6 attached to the plow frame 1. The free end of the beam 2 is normally in engagement with the frame 1 and bears against the lower surface of a stop shoulder 21 situated at the upper edge of the frame and adjustable in vertical direction of a screw or the like. Slidably mounted in an aperture in the bracket 6 substantially parallel to the frame 1 is a tubular rod 7. Said rod 7 carries a spring 10 which is clamped between the bracket 6 and a fork shaped head 11 at the free end of the rod 7. Mounted on a transversely extending journal 12 carried by the fork 11 is a roller 13. The fork head 11 is slidably mounted in a bracket 14 secured to the frame 1.

Pivottally mounted at 15 in the frame 1 in front of the free end of the beam 2 is a bell 16.

crank lever 16. The lower end of the lever 16 is shaped as a fork carrying a roller 17 by means of the pivot 18. The upper end of the lever 16 is shaped as a cam 19 the foremost portion of which is concentric or substantially concentric with respect to the pivot 15. At its side facing the bracket 14 the upper arm of the lever 16 is formed with a projection 20.

10 Attached to the frame 1 on the opposite side of the lever 16 with respect to the bracket 14 is a bracket 21. Mounted on a pivot 22 in the bracket 21 is a fork-shaped lever 23. A roller 24 mounted on a pivot in the lever 23 between the arms thereof engages an elongated slot 25 formed in the lever 16. The construction of the device, as far as its further details is concerned, will best appear from a description of its operation.

15 20 In the working position of the plow base, as shown in Fig. 1, the roller 13 of the fork 11 is held by the action of the spring 10 against the rear straight edge of the upper arm of lever 16. The pressure thus resulting will be transmitted through the roller 17 to the lower edge of the front end of the beam 2 which is thus pressed upwards against the fixed stop shoulder 21 thereby maintaining the beam with its plow base in working position. Should there be any hindrance to the forward motion of the plow base sufficiently great to overcome the tension of spring 10 the plow base will turn rearwardly around the pivot 4 in the direction of the arrow.

25 30 35 In this turning movement the front end of the beam 2 is depressed causing the lever 16 to turn to the position shown in Fig. 2, whereas the fork 11 which is movable parallel to the frame 1 will be pressed rearwardly by the upper arm of the lever 16 while compressing the spring 10 until that portion of the surface 19 which is concentric with respect to the pivot 15 comes into contact with the roller 13. In this turning movement of the lever 16 the fork-shaped lever 23 will be moved downwardly due to the engagement between its roller 24 and the slot 25 in lever 16. At the time by which the roller 13 is about to slide up on the concentric portion 50 55 of cam surface 19 the roller 24 has been moved by the slot 25 to a position in which the free end of the lever 23 has come into contact with the roller 13, and during the continued turning movement of the lever 16 in order to allow the free end of the beam 2 to pass beyond the roller 17 the action of the spring 10 will, consequently, be transmitted to the fork-shaped lever 23. The point of contact between the fork-shaped lever 23 and the spring controlled roller 13 is situated on the line of direction of the spring action which line also passes through the centre of movement 22 of the fork-shaped lever 23. In this way the wedge-action above referred to will be eliminated and, moreover, the

stress on the various parts as well as the friction therebetween will be considerably reduced.

In order to enable a compression of the spring 10 by hand for the purpose of dismantling the device the outer end of the rod 7 is internally screw-threaded and, secured to the bracket 6 is a transversely extending bolt 8 which engages a longitudinally extending slot 9 formed in the rod 7. By means of a tool which is screwed into the tubular rod 7 until it engages the bolt 8 a compression of the spring may be effected, inasmuch as a continued in-screwing of the tool after it has come into engagement with the bolt 8 will cause a displacement of the rod outwardly.

What I claim is:—

1. In a plow the combination with the plow frame of a plow beam pivotally connected thereto, a plow base carried by said beam, a lever pivotally mounted in the plow frame to be engaged by the free end of the plow beam to hold the plow base in working position, a spring arranged to act on said lever without being mechanically connected thereto to maintain said engagement and to be compressed to allow the lever to release the plow beam, when the plow base is forced out of working position due to a resistance in the ground, and a stop member to relieve the lever from the action of the spring when compressed and maintain the spring in compressed state.

2. In a plow the combination with the plow frame of a plow beam pivotally connected thereto, a plow base carried by said beam, a lever pivotally mounted in the plow frame to be engaged by the free end of said beam to hold the plow base in working position when in normal position, a spring arranged to act on said lever without being mechanically connected thereto to maintain said engagement, said lever being so shaped as to be capable of releasing the plow beam after a slight compression of the spring due to a slight turning of the lever from its normal position, and a stop member arranged to be out of engagement with the spring when the lever is in normal position, and to be brought to a position in which it relieves the lever from the action of the spring and maintains the spring in compressed state after the lever has been swung from its normal position sufficiently to release the plow beam.

3. In a plow the combination with the plow frame of a plow beam pivotally connected thereto, a plow base carried by said beam, a lever pivotally mounted in the plow frame to be engaged by the free end of said beam to hold the plow base in working position when in normal position, a spring arranged to act on said lever without being mechanically connected thereto to maintain said engagement, said lever being so shaped as to compress the

- spring during a first turning from its normal position and be capable of continued turning independently of the spring to enable releasing of the plow beam, and a stop member controlled by said lever in such a way as to be out of engagement with the spring in the normal position of said lever and be brought to a position in which it maintains the spring in compressed state after the lever has been turned to compress the spring. 4. In a plow the combination with the plow frame of a plow beam pivotally connected thereto, a plow base carried by said beam, a lever pivotally mounted in the plow frame to be engaged by the free end of said beam to hold the plow base in working position when in normal position, a spring arranged to act on said lever without being mechanically connected thereto to maintain said engagement, said lever being so shaped as to compress the spring during a first turning from its normal position and be capable of continued turning independently of the spring to enable releasing of the plow beam, another lever pivotally connected to a bracket on the plow frame, and a connection between said first-mentioned lever and said other lever so arranged as to hold said other lever out of engagement with the spring in the normal position of said first-mentioned lever and bring it to a position in which it maintains the spring in compressed state after the first-mentioned lever has been turned to compress the spring. 5. In a plow the combination with the plow frame of a plow beam pivotally connected thereto, a plow base carried by said beam, a lever pivotally mounted in the plow frame to be engaged by the free end of said beam to hold the plow base in working position when in normal position, a spring arranged to act on said lever without being mechanically connected thereto to maintain said engagement, said lever being so shaped as to compress the spring during a first turning from its normal position and be capable of continued turning independently of the spring to enable releasing of the plow beam, another lever pivotally connected to a bracket on the plow frame situated on or substantially on the line of direction of the action of said spring, and a connection between said first-mentioned lever and said other lever so arranged as to hold said other lever out of engagement with the spring in the normal position of said first-mentioned lever and bring it to a position in which it maintains the spring in compressed state after the first-mentioned lever has been turned to compress the spring. 6. In a plow the combination with a plow frame of a plow beam pivotally connected thereto, a plow base carried by said beam, a two-armed lever pivotally mounted in the plow frame, one arm of said lever being adapted to be engaged by the free end of the plow beam to hold the plow base in working position when in normal position, a spring to act on the other arm of said lever without being mechanically connected thereto to maintain said engagement, said other arm of the lever being so shaped as to compress the spring during a first turning of the lever from its normal position and be capable of continued turning independently of the spring so as to be allowed to release the plow beam after slight compression of the spring, another lever pivotally connected to a bracket on the plow frame, a connection between said other lever and said first-mentioned lever so arranged as to hold the other lever out of engagement with the spring in the normal position of the first-mentioned lever and bring it to a position to serve as a stop for said spring to relieve the first-mentioned lever from the action of the spring after said lever has been moved to compress the spring, and means on said first-mentioned lever operated by the plow beam automatically to restore the engagement between the plow beam and said lever by a backward drive of the plow. 7. In a plow the combination with the plow frame of a plow beam pivotally connected thereto, a plow base carried by said beam, a two-armed lever pivotally mounted in the plow frame, one arm of said lever being adapted to be engaged by the free end of the plow beam to hold the plow base in working position when in normal position, a spring, a rigid guide member connected to the plow frame, a slideable member mounted in said guide member and connected to the spring to engage the other arm of said lever under the action of the spring, said other arm being so shaped as to compress the spring during a first turning of the lever from its normal position and be capable of continued turning independently of the spring so as to be allowed to release the plow beam after slight compression of the spring, another lever pivotally connected to a bracket on the plow frame, a connection between said other lever and said first-mentioned lever so arranged as to hold the other lever out of engagement with said slideable member in the normal position of the first-mentioned lever and bring the other lever to a position to serve as a stop for said slideable member to relieve the first-mentioned lever from the action of the spring after it has been moved from its normal position to compress the spring, and means on said first-mentioned lever operated by the plow beam automatically to restore the engagement between the plow beam and the first-mentioned lever by a backward drive of the plow. In testimony whereof I have signed my name.
